UNITED STATES PATENT OFFICE.

CHARLES A. LOONEY, OF MUSKOGEE, OKLAHOMA.

NECKTIE PRESS.

Application filed April 29, 1926. Serial No. 105,460.

This invention relates to a necktie press particularly adapted for domestic use.

The primary object of the invention is to provide a press of that type which will accommodate a number of neckties and permit access thereto without disarrangement of all of the ties contained therein when one tie is removed, and further, to provide means for preventing soiling of the neckties and retaining the same in pressed condition at all times by weight means applied and concealed within the top cover member of the press.

A further object of the invention is to provide a press of the character specified wherein the pressure on the neckties held within the press is equally distributed over the entire surface of a plurality of leaves between which the ties are disposed, the pressing operation being effected automatically as soon as a tie is placed within the press without the use of screws, clasps, binders, springs or other extraneously operating means.

A still further object of the invention is to provide a necktie press of the class specified which is simple in its construction and materially advantageous in its operation and which may be manufactured and sold at a comparatively small cost.

The invention consists in the preferred construction and arrangement of the improved necktie press which will be more fully hereinafter described and claimed.

In the drawings:

Fig. 1 is a perspective view of the improved press, showing the top cover open and a tie placed in position therein and shown in dotted lines.

Fig. 2 is an end elevation of the improved press in closed condition.

Fig. 3 is a sectional perspective view of a portion of the cover of the improved press.

The numeral 5 designates a plurality of leaves mounted between a top cover 6 and a back cover 7. The covers 6 and 7 are preferably formed of thicker material than the leaves 5, and the covers and leaves are hinged, as at 7, by a very simple form of hinge construction consisting of strips of suitable strong material comprising securing members which are provided with adhesive material to securely fasten them throughout their length to the inner opposing sides of the covers and leaves, an intervening loop or fold 9 being disposed between

and continuous with the strips 8 and freely movable between the covers and leaves when the latter are opened and closed. This form of hinge connection is somewhat similar to some forms of signatures adopted in book-binding operations. The material of the several leaves 5 and the top and bottom covers 6 and 7 may be of any character adapted for the purpose, but it has been found in practice that heavy cardboard will be very serviceable. The number of leaves 5 may be increased in accordance with the general dimensions of the improved press, but for individual use it will be understood that the more compact the improved press the greater its advantage, or the minimized number of leaves employed will be ample to fulfill the function for which the press for individual use is intended to perform. In the present instance the press is shown having a capacity for four neckties.

The most essential feature of the invention is the novel manner of applying weight means to the top cover 6, this weight means consisting of lead or other metal weight strips 10, which are inserted and fixed in longitudinal seats or grooves 11 opening through the upper surface of the top cover. The metal weight strips 10 are of the same length as the top cover and so disposed as to equally distribute the weight thereof on the ties enclosed between the leaves 5 when the top cover 6 is closed over the said leaves as shown by Fig. 2. The bottom cover 7, of thicker material, provides a stable base support for the leaves 5 and cover 6 above, and the leaves are primarily held apart at their hinged or back edges by the loops 9, which serve as separators so that the leaves and covers, when clear of neckties, converge towards the free side edges thereof when the improved press is closed. When the neckties are inserted between the top cover and next adjacent leaf and between the leaves themselves and also between the lower leaf and bottom or back cover, the leaves and top cover assume a parallel or nearly parallel relation, owing to the thickness of material of the ties between the said parts, and the weight pressure imposed through the weight means carried by the top cover 6 is equally distributed, as above noted, over the ties enclosed and operates to press out wrinkles which may have been produced in ties that have been worn.

When it is desired to use one of the ties

disposed in the press, the top cover is opened and the tie removed from between the leaves or from between the covers and the leaves, and after it has been worn and becomes wrinkled or distorted, it is placed regularly between the parts of the improved press and again subjected to the pressing operation. By means of the improved press, neckties may be maintained at all times in good wearable condition.

It is proposed to apply a suitable ornamental strip or sheet over the top cover 6, the hinged edges of the leaves 5 and cover 7 and fully over the underside of the said latter cover. This finishing strip or sheet may be of any suitable material and is preferably applied by means of a suitable adhesive substance.

From the foregoing it will be seen that all 20 clasps, springs, clamps and the like are eliminated from the improved press and that the latter is of a simplified form and reduced in cost of manufacture and consequently reduced in sale price, and moreover, 25 the improved device is of a strong and durable nature and not only serves to maintain

neckties in good wearable condition but also shields the neckties from exposure to dust.

What is claimed as new is:

A necktie press of the class specified, comprising top and back covers and leaves arranged between the covers, the covers and leaves being hingedly connected at their rear edges by strips secured thereto and formed with intermediate loop spacers projecting inwardly between the covers and leaves and also between the leaves to hold the latter apart, the top cover and leaves when in normal empty condition all converging downwardly towards the back cover to increase 40 the effective pressing action equally on the neckties when the latter are inserted between the leaves and said cover and also the bottom cover, the leaves and top cover, when neckties are interposed between the same, assuming a substantially parallel relation, and weight means imbedded and concealed in and permanently carried by the top cover.

In testimony whereof I have hereunto set my hand.

CHARLES A. LOONEY.
